Des. 207,465
Patented Apr. 18, 1967

207,465

MAGNETIC TISSUE BOX HOLDER

Robert E. Dudley, Golden, Colo. (1765 Sherman St.,
Denver Colo. 80203), and Walter L. McDaniel, 940
Clarkson St., Denver, Colo. 80218

Filed Oct. 27, 1965, Ser. No. 87,945

Term of patent 3½ years

(Cl. D58—13)

FIG. 1 is a top perspective view of a magnetic tissue box holder showing our new design;
FIG. 2 is an end elevational view thereof;
FIG. 3 is a bottom plan view thereof; and
FIG. 4 is a side elevational view thereof.

We claim:

The ornamental design for a magnetic tissue box holder, substantially as shown.
